UNITED STATES PATENT OFFICE.

WILLIAM A. MOSBY, OF COTTON PLANT, ARKANSAS.

TARGET.

1,341,814.

Specification of Letters Patent.

Patented June 1, 1920.

Application filed September 27, 1919. Serial No. 326,900.

To all whom it may concern:

Be it known that I, WILLIAM A. MOSBY, a citizen of the United States, residing at Cotton Plant, in the county of Woodruff 5 and State of Arkansas, have invented certain new and useful Improvements in Targets, of which the following is a specification, reference being had to the accompanying drawings.

10 This invention relates to certain improvements in targets, and it is an object of the invention to provide a novel and improved device of this general character comprising a sectional body provided with means for 15 normally maintaining the sections in desired relation and which means comprises a trigger for rendering said means operative and which trigger, when struck by a suitable projectile, assumes a position to permit the sections of the body to have relative movement.

Another object of the invention is to provide a novel and improved device of 20 this general character including a body in simulation of a human figure and which body comprises separable sections movable one with respect to the other to imitate a person bowing, together with means rendered operative under force or impact to 25 cause the desired relative movement of one of the sections with respect to the other.

An additional object of the invention is to provide a novel and improved device of 30 this general character which is provided with means to attract attention thereto and which serves to afford amusement and which also tends to cultivate skill in the throwing of projectiles by individuals.

The invention consists in the details of 35 construction and in the combination and arrangement of the several parts of my improved target whereby certain important advantages are attained and the device rendered simpler, less expensive and otherwise 40 more convenient and advantageous for use, as will be hereinafter more fully set forth.

The novel features of my invention will hereinafter be definitely claimed.

In order that my invention may be the 50 better understood, I will now proceed to describe the same with reference to the accompanying drawings, wherein:

Figure 1 is a view in front elevation of 55 a target constructed in accordance with an embodiment of my invention;

Fig. 2 is a fragmentary view, partly in

elevation and partly in section, illustrating the latch, as herein embodied;

Fig. 3 is a view partly in side elevation and partly in vertical section, of a target 60 as herein disclosed;

Fig. 4 is an enlarged fragmentary view in horizontal section of the mechanism herein embodied for oscillating the head of the target, and, 65

Fig. 5 is a fragmentary view partly in side elevation and partly in section, of the mechanism illustrated in Fig. 4.

As disclosed in the accompanying drawings, B denotes the body in its entirety of 70 my improved target and which body consists of two separable sections 1 and 2. The body B is in simulation of a human figure and the sections 1 and 2 are connected at what may be termed the waist line of 75 the body. The connection between the sections 1 and 2 comprises the spring hinges 3 which serve to constantly urge the upper section in a downward direction so that under certain conditions the figure will 80 simulate a person bowing. The sections 1 and 2 of the body are hollow and the front or forward walls of the sections 1 and 2 at their meeting edges are provided with 85 registering recesses 4 which coöperate to afford a target opening through which it is adapted to throw a ball or other projectile of sufficient weight. The walls of the recesses 4 are preferably beveled.

The inner face of the front wall of the 90 upper section 2 is provided with an inwardly directed keeper 5 with which engages a spring latch 6 carried by the upper end portion of a vertically disposed trigger 7. The lower end portion of the trigger 95 7 is pivotally engaged as at 8 with the inner face of the front wall of the lower section 1 and said trigger 7 is constantly urged forwardly by the spring 9 contacting with the rear face of the trigger 7 and 100 suitably secured to the section 2. A person stands a desired distance away from the body B and throws a ball or other projectile with an effort to strike the trigger 7 which intersects the opening afforded by 105 the recess 4 and with the latch carried by the trigger engaged with the keeper to hold the sections 1 and 2 substantially in alignment. Upon the ball or other projectile striking the trigger 7 the force of the impact will force said trigger inwardly and 110 disengage the latch 6 from the keeper 5

whereupon the spring hinges 3 will cause the upper section 2 to swing forwardly and downwardly so that the body will simulate a person bowing.

- 5 The lower section 1 is adapted to be suitably mounted upon any desired base or foundation.

The rear wall of the upper section 2 in its lower portion is provided with a vertically directed open slot or recess 10 to provide the desired clearing so that the upper portion of the trigger 7 will offer no obstruction or hindrance to the desired swinging movement of the upper section 2.

- 15 Extending outward from the rear wall of the lower section 1 is an upwardly inclined arm 11 of desired length and which has its outer or free end portion bifurcated with a pulley 12 rotatably mounted within the
20 kerf 14 afforded by such bifurcation. Passing over the pulley 12 is a flexible member 15 secured to the outer or upper end portion of the rear wall of the section 2 so that after the section 2 is swung forwardly and
25 downwardly the same may be readily returned to its vertical position or substantially in alignment with the lower section 1 by imposing the desired strain upon the flexible member 15. When the section 2 is
30 returned to its vertical position the latch 6 carried by the trigger 7 will automatically engage the keeper 5 to hold the section 2 in such position until the latch 6 is again disengaged from the keeper 5 upon movement
35 of the trigger 7.

The opposite sides of the upper section 2 at the top portion thereof are provided with the downwardly directed members 16 each in simulation of an upper arm and pivotally engaged with the lower or free end portion of each of said members 16 is a member 17 in simulation of a fore arm. Secured to each of the members 17 is a flexible member 18 which extends upwardly and through the upper part of the section 2 and then extends downwardly and operatively engages with the resilient member 19 extending rearwardly from the lower section 1. As the section 2 swings forwardly and downwardly the members 17 will also swing so that the general effect of the bowing of the figure is materially increased and in a manner to further amuse the spectator.

Resting upon the upper neck portion of the section 2 is a member 20 in simulation of a human head and interposed between said member and the upper or neck portion of the section 2 are the anti-friction members 21 whereby the member or head 20 may have rotary or oscillating movement with a minimum of frictional resistance. Depending from the member of head 20 is a shank 22 which extends within the upper portion of the section 2. The lower portion of the shank 22 is provided with a gear 23 having

in mesh therewith the opposed racks 24. The racks 24 are supported for reciprocation and are adapted to move in unison but in reverse directions and each of said racks 24 is engaged through the medium of the link 25 with an operating wheel 26. Each of the wheels 26 constitutes a gear in mesh with a pinion 27 fixed to a driven shaft 28. The driven shaft 28 is caused to rotate through the medium of a conventional type of spring motor generally indicated as M. As the shaft 28 is rotated the racks 24 are reciprocated and the reciprocation of the racks rocks or oscillates the shank 22 so that the member or head 20 is caused to turn to the right and left so that it would appear as if the body was endeavoring to observe some person or other object. The movement of the member or head effectively serves to attract attention and which is of especial advantage when the device is set up at a pleasure park or other place of amusement.

From the foregoing description, it is thought to be obvious that a target constructed in accordance with my invention is particularly well adapted for use by reason of the convenience and facility with which it may be assembled and operated and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A target of the class described comprising two superimposed sections hingedly connected, said sections being hollow and the upper section being provided with a target opening, a trigger mounted within the lower section and extending across the target opening of the upper section, and a keeper within the upper section with which the trigger engages to maintain both sections substantially in alinement, said upper section dropping by gravity when the trigger is released from the keeper. 105 110 115

2. A target of the class described comprising two superimposed sections hingedly connected, said sections being hollow and the upper section being provided with a target opening, a trigger mounted within the lower section and extending across the target opening of the upper section, a keeper within the upper section with which the trigger engages to maintain both sections substantially in alignment, said upper section dropping by gravity when the trigger is released from the keeper, and means for constantly urging the trigger in a direction toward the target opening. 120 125

3. A target of the class described comprises 130

ing two superimposed sections hingedly connected, a trigger carried by the lower section and engaging the upper section to maintain said sections substantially in alinement, 5 said trigger releasing the upper section under the influence of an impact thereon, an outstanding member carried by the lower section, and a flexible member engaged with the upper section and co-acting with the outstanding member to provide means for returning the upper section to normal position.

4. A target of the class described comprising two superimposed sections hingedly connected, means coacting with the sections for 15 maintaining the same substantially alined, said means releasing the upper section under the influence of an impact thereon, an arm pivotally engaged with the upper section, an outstanding member carried by the lower 20 section, and a flexible member connecting the arm and the outstanding member, and freely passing through the upper section.

5. A target of the class described comprising two superimposed sections hingedly connected, means coacting with the sections for maintaining the same substantially alined, said means releasing the upper section under the influence of an impact thereon, an arm pivotally engaged with the upper section, an 25 outstanding member carried by the lower section, and a flexible member connecting the arm and the outstanding member, and

freely passing through the upper section, said outstanding member being resilient.

6. A target of the class described comprising two superimposed sections hingedly connected, the connected ends of said sections having recesses registering when the sections are substantially alined to provide a target opening, a trigger carried by one of the sections for locking engagement with the second section to maintain said section substantially in alinement, said trigger extending across the target opening.

7. A target of the class described comprising two superimposed sections hingedly connected, means coacting with the sections for maintaining the same substantially alined, said means releasing the upper section under the influence of an impact, an arm pivotally 40 engaged with one of the sections, and means for imparting movement to said arm when the upper section is released.

8. A target of the class described comprising two sections supported for relative 45 movement, releasable means for maintaining said sections substantially alined, a head rotatably supported by one of the sections, and means confined within said section for oscillating said head, whereby said head is 50 moved in all positions of said section.

In testimony whereof I hereunto affix my signature.

WILLIAM A. MOSBY.
